(57) **CLAIM**

The ornamental design for a traffic control cabinet, as shown and described.

DESCRIPTION

FIG. 1 is a front view of a traffic control cabinet showing our new design;

FIG. 2 is a right side perspective view thereof; FIG. 3 is a second right side perspective view thereof; and, FIG. 4 is a front perspective view thereof.

The broken line showing of handles, vents, a front plate, and internal structures is included for the purposes of illustrating portions of the "article" and form no part of the claimed design.

1 Claim, 4 Drawing Sheets

FIG. 1

FIG. 2

FIG. 3

FIG. 4
